Primary Examiner — Paula Greene(74) *Attorney, Agent, or Firm* — Daniel R. Kimbell; Karish & Bjorgum, PC(57) **CLAIM**

The ornamental design for handle, as shown and described.

DESCRIPTION

FIG. 1 is front right perspective view of the handle of the invention.

FIG. 2 is a front view of the handle of FIG. 1.

FIG. 3 is a rear view of the handle of FIG. 1.

FIG. 4 is a bottom view of the handle of FIG. 1.

FIG. 5 is a top view of the handle of FIG. 1.

FIG. 6 is a right side view of the handle of FIG. 1; and, FIG. 7 is a left side view of the handle of FIG. 1.

The features shown in dashed lines form no part of the design and are not claimed.
